UNITED STATES PATENT OFFICE.

WALTER G. HOLMES, OF ROCHESTER, NEW YORK.

STERILIZER.

1,252,571.

Specification of Letters Patent.

Patented Jan. 8, 1918.

Application filed June 15, 1915. Serial No. 34,287.

To all whom it may concern:

Be it known that I, WALTER G. HOLMES, a citizen of the United States, and resident of Rochester, in the county of Monroe and State of New York, have invented certain new and useful Improvements in Sterilizers, of which the following is a specification.

This invention relates to sterilizing apparatus of the kind in which boiling water is used for the sterilization of surgical instruments and vessels, and in which water is itself sterilized for surgical use.

It has been common to employ a sterilizer, for the purpose in question, in which an instrument-sterilizing tank or boiler, and a tank or boiler in which water may be heated and sterilized for outside use, are mounted upon or in a cabinet in which provision is usually made, also, for a receptacle in which instruments and material may be stored, and for a table or top upon which articles may be conveniently placed either before or after sterilization. The present invention relates to devices of this general character, and one object of the invention is to so arrange the various parts of the apparatus as to secure compactness and minimize the floor-space occupied, and at the same time to produce a sterilizer which is convenient in operation and in which all parts, when not in use, are inclosed within a single cabinet of simple form and neat appearance.

Another object of the invention is to provide convenient means for supporting articles within a sterilizing boiler, and for transferring such articles to and from the boiler.

A third object of the invention is to provide a gage, to indicate the amount of water in a sterilizing boiler, which is combined in a novel and effective manner with the cabinet in which the boiler is inclosed, and to provide, furthermore, for the proper heating and sterilizing of that part of the water which is inclosed within the gage.

To the foregoing ends the invention resides in the various features of construction and arrangement of the sterilizer illustrated in the accompanying drawings and herein-after described, as it is defined in the claims.

In the accompanying drawings:—

Figure 1 is a vertical section, looking from right to left, of a sterilizer embodying the present invention;

Fig. 2 is a horizontal section on the line 2—2 in Fig. 1;

Fig. 3 is a vertical section showing the parts in a different position from that of Fig. 1;

Fig. 4 is a side-elevation of the gage-glass mounting, as seen from within the cabinet; and

Fig. 5 is a section on the line 5—5 in Fig. 4.

The invention is illustrated as embodied in a sterilizer having a sheet-metal cabinet 10 of rectangular cross-section, within which all the other parts of the apparatus are inclosed. The top of the cabinet is normally closed by a cover 11, which is hinged at the rear, and which is at such a height from the floor upon which the cabinet stands as to constitute a convenient table for the reception of the various articles in connection with which the sterilizer is used.

The lower part of the cabinet is closed off from the upper part by a horizontal partition 42, and it provides a convenient receptacle for instruments or materials, being accessible at the front through a hinged door 12.

Above the partition 42 is located a boiler 13 in which instruments and vessels may be sterilized, this boiler being elongated in form so as to extend nearly from side to side of the cabinet. The boiler 13 is heated by a gas-burner 14 of ordinary form, and is inclosed within a casing 31 to retain the products of combustion of the burner in contact with the boiler.

One important feature of the invention resides in the means for affording access to the boiler 13, and for introducing articles to and removing them from this boiler. Above the boiler 13 the casing is provided, at the front, with an opening which is normally closed by a door 15 mounted on hinges 16 at its lower edge. This door is held closed by buttons 17 at its upper edge. Associated with the door 15 is a sheet-metal cover 18 which normally closes the top of the boiler 13, as shown in Fig. 1. This cover is cylindrically curved, and it is fixed, at its ends, to brackets 19 connected with the door 15. When the door is opened it may swing downwardly into the position of Fig. 3, and in doing so it raises the cover 18 from the

boiler, the cover then swinging outwardly to a position in front of the cabinet. For the convenient manipulation of the door it is provided with a crank-handle 41 at one end. The articles to be sterilized are placed in a basket comprising sheet-metal end-members 20 and rods 21 which connect the end-members at their lower edges. Each end-member is provided with an upper portion 22 in the form of a handle, by which the basket may be conveniently manipulated. From each of the brackets 19 a support 23 extends upwardly and is provided with a pin 24, and each of the end-members 20 has a hook-shaped portion 25 adapted to rest upon one of the pins 24 and thereby to support the basket pivotally. When articles are to be introduced into the boiler 13 they are placed in the basket and the basket is mounted above the cover 18, as just described and as shown in Fig. 3. The door 15 is then swung upwardly and closed, and in this manner the cover 18 is swung back to the position of Fig. 1. During this swinging movement the basket rocks upon the pivot-pins 24 and assumes finally the position shown in Fig. 1, in which it and its contents are immersed in the water contained in the boiler 13. When the sterilization has been completed the parts are returned to the position of Fig. 3, and at this time the cover 18 serves as a pan to catch any water which drips from the basket and its contents. A flange 26 at the inner edge of the cover 18 serves to retain the water so collected in the cover until the cover has next been swung to the position of Fig. 1, whereupon the water is discharged back into the boiler 13.

In the arrangement just above described, it is highly important to note that the so-called tray or basket, in the opening and closing positions of the boiler cover, is directly supported from the latter, free for pivotal movement, so that it will always be gravity-held, right side up. The brackets 19 project from the cover approximately at a right angle thereto, or at any rate, they are so projected from the said cover that when the cover is in an upright position, the tray will be supported above the boiler and the drippings therefrom will then be directed back into the boiler. As the cover is turned further outward, or toward its extreme open position, it moves under the tray and then serves as a drip pan therefor. The connection between the cover and the tray is a direct pivotal connection, no intervening parts other than the brackets being required, and these brackets are either integral with or otherwise rigidly secured to the cover so that they constitute a part thereof.

In addition to the boiler 13 the apparatus is provided with a boiler 27 in which water may be heated and sterilized for use outside of the apparatus, and with a third boiler 28

which may be used to sterilize articles which cannot conveniently be placed in the basket. The boiler 27 is heated by a burner 29, which is supplied with a mixture of gas and air, in the usual manner, through a tube 39 connected with a mixing-valve 40 at the outside of the cabinet. Since the water is drawn off from time to time, as required, from the boiler 27 a gage is desirable to notify the user when this boiler requires replenishing, and one feature of the invention resides in the novel and simple manner in which this gage is constructed and is combined with the cabinet in which the boiler is inclosed. For this purpose one side-wall of the cabinet is provided with an elongated vertical opening behind which an elongated recessed metal member or body 33 is fixed, this member being connected at top and bottom, respectively, with water-pipes 34 and 35 extending to the upper and lower parts of the boiler 27. The gage-glass 36 is in the form of a flat strip of plate-glass, which is clamped between the member 33 and the side of the casing, the parts being fixed together by screws 37, and waterproof gaskets of rubber, or other suitable material, being interposed between the gage-glass and the casing and the member 33, as shown in Fig. 5. Between the member 33 and the gage-glass the water rises to the same level as in the boiler, and is visible through the opening in the wall of the cabinet. For convenience the faucet 44, through which water is drawn from the boiler 27, is attached to the lower end of the member 33.

The use of a gage of any kind with a boiler in which water is sterilized has heretofore been considered objectionable, for the reason that the water which is contained in the gage and in the passages connecting it with the boiler tends to remain at a lower temperature than the water in the boiler, and is not subject to the thermal circulation in the boiler, so that it may fail to be properly heated and sterilized. A feature of the present invention resides in the provision of means for the express purpose of heating the water within the gage and the pipes connecting it with the boiler, so as not only to sterilize the water in this part of the apparatus, but also to maintain a circulation through the gage by which all stagnation of the water therein is prevented. For this purpose I provide a branch-pipe 38 leading from the tube 39 through which the burner 29 is supplied, and this branch-pipe has an open end located just beneath the pipe 35 by which the lower end of the gage is connected with the boiler 27. When the burner 29 is lighted the mixture of gas and air which emerges through the pipe 38 is also lighted, and the flame playing upon the pipe 35 heats the water therein and causes it to rise and flow through the gage.

The boiler 28 is heated in the same manner as the boiler 27, and both of these boilers are inclosed in casings 30 to retain the products of combustion. Outlets from the casings 30 and 31 are provided by a branched flue 32 which may be connected with a chimney in the usual manner.

The boilers 27 and 28 are provided with removable covers 45 through which they 10 may be filled, and access to them is provided by opening the cover 11 at the top of the cabinet. The necessity of opening the cover 11 is, however, comparatively infrequent, while the most frequent use is made of the 15 sterilizing boiler 13, and the provision of means for access to this boiler without the necessity of opening the cover 11 is a valuable practical feature of the apparatus since it permits the cover 11 to be conveniently 20 used as a table while instruments are being placed in and removed from the boiler 13.

The inclosing of all of the boilers within a single cabinet not only reduces the floor-space occupied by the apparatus to a minimum, but also produces a neat and compact 25 appearance.

My invention is not limited to the embodiment thereof hereinbefore described and illustrated in the accompanying drawings, 30 but it may be embodied in various other forms within the nature of the invention as it is defined in the following claims.

I claim:—

1. A device of the kind described, comprising a liquid container having a cover hinged thereto at one side, said cover having a rigid bracket projecting from the inner face thereof, a distance approximately one-half the width of said cover, and a gravity-arighted 35 tray connected to the said bracket by a pivot that moves on the arc of a circle having its center at the axis of the lid hinge and arranged to be carried thereby directly into and out of the liquid of the container by 40 closing and opening movements of said cover.

2. A device of the kind described, comprising a liquid container having a cover hinged thereto at one side, said cover having 50 a rigid bracket projecting from the inner face thereof, a distance approximately one-half the width of said cover, and a gravity-arighted tray pivotally and detachably connected to the said bracket and arranged to 55 be carried thereby directly into and out of the liquid of the container by closing and opening movements of said cover.

3. A device of the kind described, comprising a liquid container having a cover 60 hinged thereto at one side, said cover having a rigid bracket projecting from the inner face thereof, a distance approximately one-half the width of said cover, and a gravity arighted tray pivoted to said bracket and 65 arranged to be carried thereby directly into

and out of the liquid of the container by closing and opening movements of said cover, the said cover having a chamber in its underside and being arranged to turn under said tray when in an extreme open position, 70 and then serving as a drip pan.

4. A sterilizer comprising a hot water tank, a hinged cover for the tank having a chamber in its underside, and an instrument support and drain tray pivotally suspended 75 from said cover and adapted to at least partially enter the chamber of said cover when the latter is in an open position.

5. The combination with an upright wall, 80 of a hinged container adjacent to one side of said wall, said wall having a passageway above said container, a door hinged to said wall for opening and closing the passageway thereof, a cover for said liquid container attached to said door and projecting therefrom approximately at a right angle, said cover, on its underside, having rigid brackets projecting centrally therefrom and depending into said liquid container when said cover is closed, and a tray attached to 85 said brackets by axially aligned pivots that move on the arc of a circle having its center at the axis of the lid hinge, gravity-supported therefrom and movable into and out of the liquid of said container, by closing 90 and opening movements of said door and cover.

6. The combination with an upright wall, 95 of a hinged container adjacent to one side of said wall, said wall having a passageway above said container, a door hinged to said wall for opening and closing the passageway thereof, a cover for said liquid container attached to said door and projecting therefrom approximately at a right angle, said cover, 100 on its underside, having rigid brackets projecting centrally therefrom and depending into said liquid container when said cover is closed, and a tray pivotally attached to said brackets, gravity-supported therefrom 105 and movable into and out of the liquid of said container, by closing and opening movements of said door and cover, the said cover having a chamber in its underside into 110 which said tray, at least partially, enters 115 when said door and cover are in opened position.

7. A sterilizer comprising a hot water tank, a cover hinged thereto at one side, an instrument supporting and draining tray, 120 and a direct connection between said tray and cover free from and independent of said tank, suspending said tray within said tank and permitting said tray to maintain a horizontal position for any position of said 125 cover under the action of gravity.

8. The combination with an upright wall, 130 of a hinged container adjacent to one side of said wall, said wall having a passageway above said container, and a door hinged to

said wall for opening and closing the passageway thereof, a cover for said liquid container attached to said door and projecting therefrom approximately at a right angle, 5 said cover, on its underside having rigid brackets projecting centrally therefrom and depending into said liquid container when said cover is closed, and brackets having lat-

erally projecting studs, and a tray provided at its ends with handles and with 10 open notches adjacent said handles, said notches engaging said studs and affording detachable pivotal connections between said tray and brackets.

WALTER G. HOLMES.
